UNITED STATES PATENT OFFICE

JAMES A. MCNEY, OF HARDING, PENNSYLVANIA

STEAM AND HOT WATER GENERATOR

Application filed September 12, 1932. Serial No. 632,844.

This invention appertains to new and useful improvements in liquid heaters and vaporizers, and more particularly to a heater of the electrical type.

5 The principal object of this invention is to provide a heater for boilers and the like wherein an electrical element is involved and wherein the heater is in the form of a unit capable of being easily inserted into and removed with respect to a boiler.

10 Other objects and advantages prevail and will be observed from the following specification:

In the drawings:—

15 Figure 1 represents a vertical sectional view through a boiler showing the heating unit installed therein.

Fig. 2 represents a horizontal sectional view on line 2—2 of Fig. 1.

20 Fig. 3 represents a bottom plan view of the boiler.

Fig. 4 represents a vertical sectional view through the heating unit.

25 Fig. 5 represents a bottom plan view of the heating unit.

Fig. 6 represents a cross sectional view taken substantially on line 6—6 of Fig. 4.

Referring to the drawings wherein like numerals designate like parts, it can be seen 30 that numeral 5 represents the boiler provided with the head 6 and the bottom 7. This boiler is mounted on suitable legs 8 and has the inlet pipe 9 and outlet pipe 10 in the usual manner.

35 In carrying out the present invention the bottom plate 7 is provided with a circular opening therein for receiving the barrel 11 of the heating unit generally referred to by numeral 12.

40 This barrel 11 at its lower end is fixed to the closure plate 13 which has openings 14 therein for receiving bolts 15. These bolts 15 are disposed thru openings in the bottom plate 7 surrounding the aforementioned 45 opening therein and are equipped with nuts 16 so that the plate 13 can be clamped against the bottom of the plate 7 in a snug manner, and if desired, suitable packing material can be interposed between the plate 13 and the 50 plate 7.

In the barrel 11 in spaced relation with respect to the plate 13 is a partition 17 having openings therein corresponding to the shape of the tubes 18 and 19. These tubes 18 are 55 of the flat type whereas the tubes 19 are of

the cylindrical type. These tubes 18 and 19 are alternately placed in a circular arrangement and extend vertically within the barrel 11, the lower ends extending through the openings in the lower plate 17, while the upper ends extend through corresponding openings in the top 20 of the barrel.

60 The barrel 11 is provided with openings 21 therein between the plate 13 and the partition 17 so that water can enter the barrel from the interior of the boiler 5 and pass upwardly through the tubes 18 and 19 to discharge through the upper end of the unit 12.

65 Numeral 22 represents a dielectric conduit extending upwardly through the plate 13 to meet the plate or partition 17 and this merges at its lower end in a shell 23 receiving the electrical connector 24. Numeral 25 represents electrical conductor wires leading to the connector 24. In connection with the electrical connector 24 is an electrical heating element 26 which extends upwardly and terminates within the shell or barrel 11. (See Fig. 4).

70 While the foregoing specification sets forth the invention in specific terms, it is to be understood that numerous changes in the shape, size, and materials may be resorted to without departing from the spirit and scope of 75 the invention as claimed hereinafter.

Having thus described my invention, what I claim as new is:—

75 In a boiler, a heating device comprising a barrel having one end closed and adapted for attachment to the boiler, the opposite end of the barrel being closed, a plurality of water tubes extending longitudinally in the barrel, a partition across the interior of the barrel in close spaced relation to the attaching end of the barrel defining a water receiving chamber and a heating chamber, said barrel being provided with an opening at the water receiving chamber, said water tubes opening at their ends through the said partition and second mentioned end of the barrel, and a heating element extending longitudinally in the barrel at substantially the longitudinal axial portion thereof and in respect to which the tubes are radially disposed.

105

JAMES A. MCNEY.
